UNITED STATES PATENT OFFICE.

WILLIS MITCHELL, OF MALDEN, MASSACHUSETTS, ASSIGNOR TO WILLIS MITCHELL COMPANY, INC., OF NEW YORK, N. Y., A CORPORATION OF NEW YORK.

STEAM-GENERATOR.

1,139,430.

Specification of Letters Patent.

Patented May 11, 1915.

Application filed September 29, 1913. Serial No. 792,297.

To all whom it may concern:

Be it known that I, WILLIS MITCHELL, a citizen of the United States, residing at Malden, in the county of Middlesex and 5 State of Massachusetts, have invented certain new and useful Improvements in Steam-Generators, of which the following is a specification.

The object of this invention is the generating of steam by the more complete and effectual utilization of vibration, adapting and applying the positive and negative action produced by heat and cold, in the construction of a steam-generator, non-explosive, constant in reference to power, and capable of providing an excess of dry, anhydrous, or superheated, steam, by one single operation, and without the use or need of any super-heater or steam-dome for additional treatment, in quantity beyond what the engine can consume, and supplying the same in gaseous form and an auxiliary air-tank, utilizing the same by its expansive power therein to force water to the generator. The steam thus generated is higher in degree and more powerful than that recognized under the commonly accepted term, "superheated;" it is steam more aeriform, more refined, than that which has been 30 known as "superheated." Its vibrating rate or degree is such that a match presented to it, after it has passed through the engine, is instantly ignited by the friction and vibratory disturbance of the escaping jet, a manifestation not possible with the steam generated, however superheated, in any boiler or generator produced prior to my invention.

My generator includes a tube wound in a 40 series of double helices arranged around the burner, and combines therewith air-pressure tanks arranged to receive the vibratory action from the helices—which vibratory action is transmitted and continued through 45 the water-pressure tank, and arranged to break up the water in the water-pressure tank into its gaseous elements, thus adding more pressure in this tank, and this supply taking the place of the water being forced 50 into the helices, and also arranged to utilize the expansive power of the air compressed in the pressure-tanks, the same continuing to force the water to the generator, thus maintaining a continuation and regularity

of power for as long a time as there is any 55 water in the pressure-tank.

Suitable means, hereinafter described, are provided for preventing any excess of pressure, for re-supplying water to the pressure-tank, and also for the absolute prevention 60 of any danger of explosion.

The constituents of the steam thus resolved are left in such condition that they can be readily condensed into water again and returned as a new supply to the helices 65 for regeneration into steam.

This generator and its appurtenances, in combination with the water-feed tank, the gas-burner and the fuel gas-generator and carbureter-injector supplying the same, together constitute my new system of steam generation, using the gas from oil as fuel. The gas-generator and burner employed herein constitute the subject matter of separate applications for patents wherein their 75 novel features are claimed. The dry and rarefied steam produced thereby is, nevertheless, easily liquefied by condensation, owing apparently to separation of constituent elements effected by the vibration aforesaid, 80 which, nevertheless, leaves them with strong tendency to reunite in liquid form, becoming water again, if desired, on being directed against a condensing plate as they leave the water-tubes of the generator. 85

After coming to the conclusion that water is evaporated and steam is produced by vibration, brought about by positive and negative energies through or by contact with heat and cold, I searched for the fundamental principle and proof of the same and spent twelve years in study and experiment at heavy outlay. 90

My most interesting demonstration of the principle involved is illustrated in Figure 10 95 of the accompanying drawings, as showing the breaking up of the molecules of cold water by vibration, the water remaining cold and being converted into gaseous elements. This apparatus and its operation are described here as preliminary in their nature and not forming part of the steam-generator which is the subject of this specification, but preparing the way for adequate comprehension of the novel method of the said generator. 100

I employed, as shown in said Fig. 10, a glass U-shaped receptacle B, having metal

tops C D for its two limbs. A screw-plug E' is screwed into top C, a pump being attached thereto for pumping air into the said receptacle, a valve A preventing it from escaping. I removed said plug and filled said receptacle B two-thirds full of water, then replaced it, and attached the pump at E, pumping in air until the water was forced up the column on the opposite side, up to 10 ward the right hand cap D above the level of the connection at F', between the right limb of this receptacle and the generator coil F brazed to a copper disk C. As the air above the water in this limb cannot escape in such conditions, it makes an air-chamber or cushion and receives the same pressure as at the other limb of the receptacle and over the other column of water. The air was arranged thus to demonstrate 15 that the pressure was not maintained by steam going back into my pressure-tanks, but by the force of vibration, which was breaking up the molecules of water into gaseous form. I then poured some alcohol 20 into a receptacle M and ignited it, thereby heating the said disk and coil very quickly. I then opened the valve H of said coil and let out the contained air, which was followed by water, the latter being converted into 25 superheated steam. At the opening of said valve the water began to boil at the surface at L in left limb of the receptacle under cap C, as indicated by the arrows, being broken up at this point into gaseous elements which 30 took the place of the water that was being converted into steam. This boiling cannot be due to steam or gas passing back through the U-shaped receptacle, for it would naturally take the path of less resistance through 35 coiled tube F, escaping into the chamber at its opening J. But vibratory energy passing through the water in this manner would produce this ebullition and reduction to aero-form fluid; and such vibration is the efficient 40 agent in the case. I have caused this vibration to pass through a resistance coil, using up the energy just as if electric energy was 45 thus passing.

Besides the broad features of my invention, it includes a number of special constructions and combinations of the various parts of the generator. Thus the water-tube is wound in a series of double helices arranged around the burner and wound so 50 as to change the direction of current in each helix, and preferably to reverse the order of said changes once in the series. I also employ a double-walled generator-casing, the inner shell of which has many small 55 holes, causing the general distribution of the heated products among all parts of the helices, and combine therewith novel means for spacing the casing-shells apart and holding the helices in place; I also provide a

tank adapted to hold air under pressure 65 and connected with the helices to equalize the flow and pressure therein, the connections of said parts being provided with a by-pass and relief valve, the former tank being also connected to the water supply by 70 a pipe similarly provided with relief valve and by-pass, the effect of said pressure being to limit the pressure in said helices and guard against explosion.

The present application does not claim 75 the especial construction of the helices described nor the other details of the generator proper, these features being reserved for a new divisional application.

In the accompanying drawings: Fig. 1 80 represents a perspective view of my steam-generator, the outer shell being partly broken away; Fig. 2 represents on a larger scale a front elevation of the same, the front wall being removed to exhibit the 85 series of double helices in position; Fig. 3 represents on a still larger scale a detail perspective view of one of the double helices; Fig. 4 represents the two helices composing it, separated and set side by side; 90 Fig. 5 represents a detail view, in elevation, of the pressure-tanks and their tubular connections; Fig. 6 represents a detail view in vertical section of the air supply pipes and the concentric water connections; 95 Fig. 7 represents a detail view of a by-pass valve; Fig. 8 a detail view of a check valve; Fig. 9 a detail view of one of the bolts; Fig. 10 a diagram of certain experimental apparatus; and Fig. 11 is a detail view of 100 the shield-form valve proper of the relief or by-pass valves and its perforated disk.

The continuous water and steam pipe of my generator enters through the exterior casing thereof at *a*, preferably in the bottom, and leaves it at *b*, preferably in the top, being wound between these points into a nearly circular series of double helices, each of which consists of an outer helix 1 and an inner helix 2, this series being arranged 110 against the circular wall of the generator and around its horizontal burner 3, leaving a space 4 (Fig. 2) at the bottom, below said burner, for the generator and its pilot pre-heating devices. The forward parts of 115 these extend through the front wall of the outer casing at 5 and 6, as shown in Fig. 1, said generator and appurtenances being omitted from Fig. 2 for greater clearness and because they are not a part of this invention, their position being sufficiently indicated by Fig. 1, to aid in explaining the 120 action of the relevant elements.

The cylindrical body of the generator casing is formed of two concentric cylindrical 125 shells 7 and 8, which are spaced apart by nuts 9 on bolts 10, the shanks of which pass between the proximate helices and are pro-

vided with broad wedge-form heads 11 for holding them in place. At the ends of the series screw-tapped nuts 12, similar in form to said heads 11, are engaged by short screws 5 13, the heads of which have the form and function of said nuts 9, and drawn into the angles between the terminal helices of the series and the inner casing shell 7. By these devices 9, 10, 11, 12, and 13, all the 10 helices are securely clamped in position and a draft space 14 is provided also by them between the two shells of the casing.

As the products of combustion are inoffensive, and not great in volume, no smoke- 15 flue or funnel is needed, but the inner shell is provided at numerous points with small outlet holes 15, compelling a general distribution of the said products of combustion and heat among all the coils of the helices 20 before making their escape into space 14. The outlet shell 8 has only a single outlet 16, which is in its bottom, compelling the small streams of such heated gaseous matter, after they issue through the holes 15, 25 to pass along or around the inner shell 7 through space 14, converging at this final bottom outlet. They are hardly perceptible to one standing near, as there is no smoke or steam and the combustion is nearly per- 30 fect, mainly by reason of improvements in the generator and burner which form no part of the subject matter of this application; but also to some extent because of the tortuous path which they are compelled to 35 follow after leaving the burner, during the earlier part of which they are in or very near the flames and afterward in close contact with the heated inner shell 7.

Preferably the first winding of the water- 40 tube is in the form of the outer cylindrical helix 1 of the first double helix, reversing at the rear end thereof to wind the inner helix 2 of the same concentrically within it; then it passes to the outer helix 1 of the 45 next double helix, beginning again at the forward end thereof and so continuing until half of the series is wound, then passing in a long curve 19 outside of the position of the remainder of the series and beginning at 50 the front end of the inner helix 2 of the last double helix, reversing at the rear of this to wind the outer helix 11 of said double helix, then winding the inner helix of the next double helix, and so backward to the 55 middle of the top of the series where it ends at b. Thus the water as it turns to steam and then to permanent rarefied gaseous product, flows around the burner subject to its heat in a very devious current which is 60 suddenly reversed at the end of the first helix of each double helix, the direction from left to right being changed to that from right to left for example in each double helix of the first half of the series,

and the direction from right to left being 65 similarly changed to that from left to right in each double helix in the second half of the series, also the general course being toward the top of the series in both halves thereof. Furthermore, the winding in re- 70 versed series makes the two helices in each double helix cross each other and intercept more perfectly the radiant heat and hot gaseous matter flowing from the burner into and through said helices, in order that it 75 may be applied to the best effect. This is aided by the provision for escape in minute quantities through small outlet holes at many points, as above stated. With such a construction of the shell and helices very 80 little of the heat can fail of doing its full service. But in addition, the frequent interruptions and reversals of the water and steam current will tend to break up the particles thereof, to lessen cohesion and bring 85 it more nearly to a finely gaseous state, as is obvious when streams visibly dash together, producing spray and mist, or are torn into vapor by contact with obstacles or by friction along their beds. This enables 90 the heat to act with greater efficacy, a part of its work being done for it by more strain, jar and attrition. Also, there must be a generation of electricity and, perhaps, other subtle vibratory action, contributing to the 95 comminuting and gasifying action. The influx of water at the bottom of the generator has been found more efficient and satisfactory than if it were at the top, inasmuch as the heat derived from the burner and circu- 100 lating currents of hot gases is permitted to exert its greatest effect just before the steam leaves the generator. This is due to the fact that the gases circulate quite to the top of the generator casing and that their lighter 105 elements necessarily tend up to that so that the temperature is necessarily at its highest in the neighborhood of the outlet helix and the pipe running therefrom.

A main pressure tank 20 and auxiliary 110 pressure-tank 21, connected together by an air pipe 22, governed by a hand-operated valve 23, are attached to the rear end of the main generator casing and have the function of preventing explosion and insuring 115 regularity of steam generation in the helices, being aided therein by a system of tubes and valves, as hereinafter set forth. Auxiliary tank or reservoir 21 always contains air, normally under pressure, and never con- 120 tains anything else. The main pressure tank or reservoir 20 normally contains both water and air, the latter under pressure and acting as an air-spring on the water which enters the lower part of said tank.

From the bottom of tank 20 a short water- 125 pipe 24 extends downward, having at its lower end a coupling 25. An upright inner

1

pipe 26 extends within said tank to the upper part thereof and down to said coupling, being there connected with an air supply pipe 27, the air in which is under pressure 5 from any suitable source, said pipe being provided with an air inlet valve 35. The air pipe 26 also joins with air pipe 22 first mentioned, the latter entering the coupling from the side and having its only connection 10 with tank 20 in this way. The vertical water pipe 24, of course, has no connection with the interior of any of these pipes, but receives in its side a water pipe 28 connected with a water-supply pipe 29, which ex- 15 tends to the main reservoir by way of the pump driven by the engine. A check-valve 30 in said water-supply pipe 29 acts to prevent the water from being forced back to the pump by the tank pressure. The water 20 passes from tank 20 through a generator supply pipe 31, governed by a hand-operated valve 32, to the generator, said pipe 31 entering through the front thereof and joining the first double helix at *a* as stated. 25 This generator-supply tube 31 is provided with a by-pass branch tube 33, joining it both before and behind said valve 32, so as to provide a possible passage when this valve is closed, said by-pass being provided 30 with an outwardly opening relief or by-pass valve 34, which will open under excessive pressure to permit a back flow of water from the generator to the tank, its function being that of a safety valve arranged to cause the 35 cutting off of the steam supply. In like manner the water-supply pipe 29 is provided with a by-pass branch tube 36, running from a point of said pipe between its check valve and the pressure tank to a point 40 of said pipe on the other side of said check valve, or directly to the main reservoir. This by-pass 36 is provided with a relief valve 37, opening in case of need toward the source of water supply. A drain pipe 39, 45 having a hand-operated valve 40, connected with pipe 31, affords a convenient means of draining the water from tank 20 at will.

In operation I admit air to the tanks 20 and 21 through air-inlet valve 35 until the 50 pressure reaches one hundred pounds in the two tanks, the connection between them being open. I then pump water into the tank 20 until it compresses the air to a pressure of two hundred pounds, which point is 55 reached before the water is at the level of the vertical air pipe 26. I then cut off tank 21 from tank 20 to close their connection, thus bottling up that amount of pressure in 60 said auxiliary tank 21. I then draw out the water from the tank 20 by suitably turning valve 40 and force in air simultaneously till I have a hundred pounds of pressure, and pump in water as before till I have three hundred pounds of pressure. Then I

open the valve 23 between the two tanks 65 again and let the extra pressure into the auxiliary tank. Then I close valve 23 again. This I repeat until I have in the two tanks the pressure—for example, four hundred 70 pounds, at or a little beyond which the engine is set to run. The by-pass valves are adjusted to yield at the same pressure. The burner is then supplied and lighted and the operation of generating steam begins.

If no water be supplied to the generator 75 until its helix coils are heated exceedingly, and the water be then let in under pressure, no harm will follow. Of course, in such conditions there will be a sudden generation of steam in the hot coils, but as soon as there 80 is a pound more pressure in the helices than in the pressure-tank 20, this excess of pressure will prevent water from entering the coils and thus stop the flow to the generator, thus ending the generation of steam, for 85 the generator makes steam only while supplied with water. Should the throttle be open, it will work just the same, for there would not be any more pressure in the generator than in the pressure tank. Again, if 90 the generator be supplied with water, the fire hot and the throttle and valve 32 closed, of course steam will be generated, but without danger, for the by-pass 33 around said 95 valve 32 affords an outlet to the pressure-tank 20, its relief valve 34 yielding toward the latter. If steam be thus driven out, it will be condensed into water on the way to the pressure tank 20. If it should cause undue pressure in said tank, the water would 100 be forced out of the latter to the main reservoir or other source of water supply through the other by-pass 36 and its relief valve 37. With these provisions the steam-generator 105 is absolutely non-explosive, there being no possibility for the pressure in said generator-helices to exceed that in the pressure-tank, and the said helices are of a strength to resist a pressure of a thousand pounds.

If the generator be supplied, as is usual, 110 from a water reservoir by means of a pump operated by an engine supplied with steam by said generator, the generator discharge at *b* will be directed suitably, in part at least, to said engine, the speed being governed by the throttle in the ordinary way. Such combinations of coöperating mechanisms may safely be left untended for a 115 time. If just starting up, the inflowing water will drive the air out of the helices 120 and be converted into steam before it passes through the coils, the pump supplying the pressure-tank, the pressure-tank supplying the generator, the generator supplying the engine, and the engine driving the pump 125 in a continuous circuit of action, automatically operated and automatically regulated. The throttle and valve 32 should be

open also, and the valve governing the air connection between pressure-tanks 20 and 21, that the full requisite air-pressure may be available.

5 The pressure-tank 20, as the parts are constructed, arranged and combined by me, will be about two-thirds full of water before the relief valve 37 will open and let the water from said tank back through the by-pass 36 10 to the main source of supply, notwithstanding the pressure is being maintained; for the entering water is very light and foamy, being aerated by vibration, so that its condition is neither liquid nor gaseous, but intermediate and less adapted to transmit vibrations than either. If it were water in a pure state, or pure steam, a less volume would be supplied before the expansive power of the air compressed by it, reinforced by the inflow of such water would operate to force the water from the tank through said by-pass 36 and relief valve 37. The relief valves, of course, are adjustable to any pressure required or which may suit 25 the engine in use, but, as before stated, a working pressure limit of four hundred pounds is found convenient. It will be observed that I use air-pressure, partly produced by inlet water pressure, to balance 30 and regulate steam pressure, by letting out excessive steam or water acted on thereby and by stopping the water supply whenever the pressure exceeds the predetermined amount.

35 In the older kind of boilers it is necessary to rely on the pumps to maintain an ample supply, and, if this runs low, danger and injury will follow, but in my generator, as stated, the running low of the water can do 40 no harm.

In the changes of movement between pumping water into the pressure-tank and back and forth from the reservoir there are intervals of inaction for the valve 37, which 45 is kept open while the water goes back into the main reservoir and kept closed while the pump is forcing water into the pressure-tank, relieving both the said valve and in less degree its by-pass valve 36 from strain 50 and wear, which would be considerable if said valve were continually moving and if there never were a cessation of flow through said by-pass.

The adjustment of the relief valves 34 55 and 37 before referred to is preferably by means of a nut 40 and a screw-post 41, said nut being in contact with a helical spring 42, increasing or decreasing the tension and resisting power of said spring. By screwing 60 very tightly down the nut 40 of relief valve 37, the latter may be made practically a fixture for special occasions, as when the generator is used on a motor truck climbing a steep hill and needing abundant

water. The pumps will then at once supply 65 more water, making more steam; the extra heat required is provided by supplying extra fuel gas to the burner, using means not shown, for they do not form part of this invention, the throttle being opened 70 correspondingly wider at the same time.

I do not have to wait for steam pressure in starting, for I do not rely on the steam pressure for this, but on air and water pressure and the vibratory action, tending to 75 transform the water into gaseous condition irrespective of heat. I find that practically much less water is required for this generator than in tubular boilers commonly in use. The effervescent commotion of the 80 water due to forcing it against compressed air in pressure-tank 20 prepares it in advance, so that it is brought to a gaseous state by the use of less heat than in the ordinary generation of steam. 85

In using this generator on a motor car run by an inexperienced operator the relief valve on the by-pass of the water inlet pipe can be set to provide for a speed of nine or ten miles an hour, and the vehicle will not 90 exceed that limit, even if the throttle is wide open, unless in coasting, and the movements may be operated to retard motion even then.

By this generator I can furnish thirty- 95 horse power for ten cents an hour where it now costs sixty cents an hour with a gasoline engine of the same power.

Such a generator may of course be used to supply the pipes of a steam-heating system for house or car, and the outflowing steam directed from it upon the snow, or operating to heat snow scooped up, for supplying water is exceedingly efficient. It may also be used as a fire-extinguisher by 100 conducting a hose from the pressure-tank direct to the fire. 105

I do not confine myself to the special form of relief or by-pass valve shown, but it will often be convenient to use for valves 110 34 and 37 a semi-cylindrical depending shield or slide valve 54 adapted to cut off the back flow and carried by a piston 43, which is lifted by such flow against the resistance of a spring 42 surrounding a stem 115 46 and governed by a screw-plug 47 in the valve casing 41. This piston may have a flexible packing 50 clamped to it by a disk 51, below which is a perforated disk 45, having the slide valve or cut-off valve 54 120 properly attached to it, these parts being held together and in place by a screw 53. Their construction and combination form no part of the present invention and are illustrated merely to make the operation 125 clear.

The check valve hereinbefore described may consist of a ball valve in a casing hav-

ing a vertical inlet passage 54 under said valve at right angles to said inlet. But this, like all other details, may of course be changed by the substitution of any other 5 well known form.

Having thus described my invention, what I claim as new and desire to secure by Letters Patent is:

1. In combination with a series of water-
10 tube helices, means for heating the same and
a generator casing surrounding them, a
pressure-tank adapted to contain air under
pressure and tubularly connected to the inlet
15 end of said series, and means for opening
and closing such communication between
them at will, but permitting back flow while
it is thus closed when the back pressure from
the helices exceeds a certain degree.

2. In combination with a series of water-
20 tube helices, means for heating the same and
a generator casing surrounding them, a pres-
sure-tank adapted to contain air under pres-
sure, a pipe connecting said pipe to the
25 inlet end of said series, a hand-operated
cut-off valve in said pipe, a by-pass branch
around said valve and a relief valve in the
latter to provide for return of fluid to the
tank under pressure exceeding that of the
30 latter.

3. In combination with a series of water-
tube helices, means for heating the same and
a generator casing surrounding them, a pres-
sure-tank tubularly connected to the inlet
35 end of said series and adapted to receive
and contain air under pressure, an auxiliary
air pressure-tank, means of permitting the
passage of air from the former tank to the
latter, and the closing of such means of pas-
40 sage at will in order that air pressure may
be accumulated in the auxiliary tank to aid
the main pressure tank.

4. In combination with a series of water-
tube helices, means for heating the same and
a generator casing surrounding them, a pres-
45 sure-tank, a water-tube connecting said tank
to the inlet end of said series, an air supply
pipe to said tank supplying air under pres-
sure, an inner air pipe extending from said
air supply pipe up within said pressure-
50 tank to the upper part of the latter, an auxil-
iary air-tank, a branch air pipe connecting
said inner air pipe to said auxiliary tank,
valves controlling at will the latter air pipe
and the main air supply pipe, and means for
55 supplying water under pressure to the first
pressure tank.

5. A pressure tank in combination with an
inlet for air under pressure and means con-
60 nected to said tank adapted at will to bottle
the air under pressure and as needed to let
it act on the contents of said tank, a series of
water-tube helices supplied by said tank, a
water-pipe to said tank from the main source
65 of water supply and a by-pass and relief

valve for permitting the return of water un- 65
der excess of pressure from said tank to said
source.

6. A steam-generator in combination with
an air pressure-tank, supplying water there-
70 to, means for supplying water under pres-
sure to said tank, means for supplying air
under pressure to said tank, means, includ-
ing an automatic relief valve, for allowing
75 back flow of fluid from said generator to
said tank, and adjusting devices whereby
the yielding point of said valve may be
varied to suit the maximum pressure chosen.

7. A steam-generator in combination with
a pressure-tank supplying water under pres-
80 sure thereto, means for supplying air under
pressure to said tank, a pipe conducting
water under pressure to the latter, a valve
controlling the latter pipe, a by-pass and re-
85 lief valve, permitting water under excess of
pressure to flow back from said pressure-
tank to the main source of water supply and
means for adjusting the yielding point of
90 said relief valve.

8. A steam-generator in combination with
a pressure-tank, means for supplying air un-
90 der pressure thereto, means for supplying
water under pressure thereto provided with
an adjustable relief valve for back flow un-
der excess of tank pressure, a water pipe
connecting said tank to said generator, a 95
hand-operated valve for closing the same,
and a by-pass and adjustable relief valve al-
lowing return flow around this hand-oper-
ated valve under excess of generator pres-
95 sure and means for accumulating pressure in
100 said tank to the degree corresponding to the
adjustment of said valve.

9. In combination with a pressure-tank
and means for accumulating air pressure
therein to a predetermined degree, means for 105
supplying water thereto provided with a re-
lief valve adjustable to yield a pressure in
excess of such degree and thus permit the
return of the water, a steam generator and
means for supplying said generator with 110
water from said tank, said means being pro-
vided with a relief valve adjustable to yield
to any excess of pressure in the generator
over that in the tank.

10. A main pressure-tank with means for 115
admitting air under pressure, means for ad-
mitting water under pressure, and means for
drawing off the water at will, in combination
with an auxiliary tank protected against any
inflow of water but tubularly connected at 120
will with the air pressure in the main tank,
a steam-generator and a pipe connecting the
latter to said main tank, the latter tube and
the water supply tube being provided with
relief valves and hand-operated cut-off 125
valves, or automatically operating check-
valves being provided where necessary to
control the flow through any of the pipes.

11. The method of generating superheated steam directly from water, consisting in creating and applying vibration to break up the water into gaseous form and permitting its
5 escape rearward to an air chamber under back pressure.

In testimony whereof, I have signed my

name to this specification in the presence of two subscribing witnesses.

WILLIS MITCHELL.
